UNITED STATES PATENT OFFICE

WILLIAM D. BARTLETT, OF CINCINNATI, OHIO

COIN CONTROLLED VENDING MACHINE

Application filed May 20, 1932. Serial No. 612,614.

In the present invention I provide a coin-controlled vending machine which employs, in miniature, the well-known excavator mechanism now used in analogous art, for primarily digging into a bulk body of confection or the like, through which prizes are distributed, after which the bucket of the excavator is hoisted and transferred to a desired point where the contents of the bucket are dispensed.

The device of the present invention is automatic in its operation, yet includes manually controlled means to permit positioning of the bucket at a point of vantage above a prize, just as an excavator bucket is positioned over an object to be hoisted. However, it is an object of this invention to permit no movement of the excavator mechanism by the operator until a coin is deposited in the machine, thereby rendering the device fool proof. Even after the coin is inserted, the operator has only a limited interval within which to control movement of the mechanism for positioning the bucket at a point of supposed advantage over a prize.

A further object of the invention is to greatly simplify the excavator operating mechanism, especially in the method of raising and lowering the excavator bucket which in the present instance, is performed by cables directly connected to the driven parts of a motor at a point in proximity to the latter, with a complete absence of cable windlasses, winding drums, clutches, etc.

I have found it conducive to the effective functioning of the machine to carry all of the operating mechanism on the base of the latter, away from the zone of operation of the shovel and in a conveniently accessible position. It is therefore a coordinate object of this invention to compactly assemble all the shovel operating mechanism on a part of the base of the machine which is illuminated from the motor circuit to render the mechanism accessible and visible at all times.

Other objects of the invention will be apparent from the following description of the present preferred forms thereof, taken in connection with the accompanying drawings, wherein

Fig. 1 is a front elevational view of a vending machine constructed in accordance with the present invention;

Fig. 2 is an enlarged vertical sectional view, taken on the line 2—2 of Fig. 1;

Fig. 3 is a transverse sectional view, taken on the line 3—3 of Fig. 2, showing the operating mechanism in top plan;

Fig. 4 is a detail fragmentary sectional view of the connection between the manually operated gear and cabin shaft control disc;

Fig. 5 is a detail perspective view of the bucket hoisting, lowering and releasing mechanism;

Fig. 6 is a detail perspective view of the coin-controlled motor releasing unit;

Fig. 7 is a vertical sectional view, taken on the line 7—7 of Fig. 3, looking in the direction of the arrows and showing the coin chute and its associate mechanism in side elevation;

Fig. 8 is a detail sectional view taken on the line 8—8 of Fig. 7, looking in the direction of the arrows;

Fig. 9 is a detail fragmentary sectional view taken on the line 9—9 of Fig. 7, looking in the direction of the arrows;

Fig. 10 is a detail vertical sectional view, taken on the line 10—10 of Fig. 7;

Fig. 11 is a diagrammatical view of the circuit used in the present invention;

Fig. 12 is a detail perspective view of the bucket, showing manner of attaching cables thereto; and

Fig. 13 is a modified form of the invention, showing a manually controlled crane operating mechanism.

The device of the present invention includes a case, generally designated 13, which includes a bottom 14, with a top and side 90

walls mounted thereon. Portions of the side walls are made of glass 15, or other suitable transparent material, in order that the contents of the case will be visible for a purpose 5 more fully hereinafter set forth. The case 13 carries a display shelf or table 16 which carries confection, prizes, etc., 17.

The mechanism comprising the present invention is completely carried by a base 18, 10 which is superimposed on the bottom 14 of the case 13 and is equipped with an up-standing frame 19. A block 20 is mounted on the base 18 and carries a stub shaft 21 upon which a gear wheel 22 is rotatably mounted, 15 the latter being engaged by a worm screw 23, fixedly carried by a manually operated rod 24, which extends outwardly through the front of the case and is equipped with a hand wheel 25. The gear wheel 22 carries a disc 26 which is keyed to a shaft 27, the latter extending upwardly through the top of the frame 19 into engagement with an excavator 20 or digger cabin 28.

The cabin 28 is of conventional design and 23 is detachably engaged to the shaft 27, as indicated at 29. One end of the cabin has a crane 30 pivotally mounted thereon, the free end of the crane having twin pulleys 31 mounted therein over which cables 32 are trained. 30 One end of each cable is in engagement with an excavator bucket or shovel 33, which latter, in the present instance, is shown to be of multi-part construction, the parts thereof being hinged together to permit opening and 35 closing of the bucket. One of the cables is engaged with the parts of the bucket to effect an opening movement of the latter when pressure is exerted upon said cable, while the other cable is engaged with the axle of 40 the bucket to raise the latter without opening the parts thereof. Movement of the disc 26 imparts movement to the cabin 28 in order to correspondingly move the crane 30 and the bucket 33 supported thereby through the 45 medium of said cables.

For the purpose of effecting operation of the bucket I mount on the base 18 suitable mechanism which includes a motor 34, the shaft of which is equipped with a worm gear 50 35, which engages in mesh with a gear wheel 36 carried by a driven shaft 37. The shaft 37 also carries a worm gear, indicated at 38, which co-meshes with a complementary gear wheel 39, journaled in one end of a bracket 55 40. The base of the bracket 40 is mounted upon the base 18 and has the forward end thereof bent upwardly at right angles to provide a supporting standard 41, which supports the driven shaft 37 and likewise 60 is pivotally engaged by one end of each of a pair of arms 42. The arms 42 are intermediately engaged by hingedly connected links 43, which are pivotally mounted upon the ends of the axle which supports the gear 65 39. The free ends of the arms 42 are en-

gaged, as shown to advantage in Fig. 2, with the cables 32. It is now apparent that when the motor is operated, motion is imparted to the driven shaft 37, which in turn transmits an up and down movement to the arms 70 42, through the links 43. When one of the arms is in its lower-most position, the parts of the bucket 33 are opened, but just as soon as movement in the opposite direction of said arm is initiated, the bucket gravitates into a closed position, in order that the opposite arm in its descending movement, will, by the exertion of pressure on its cable, cause the bucket to be hoisted.

While the disc 26 is loosely mounted on 80 the gear 22, it is nevertheless apparent that the frictional engagement between said disc and gear wheel, especially under pressure of the cabin 28, will be sufficient to effect simultaneous operation of both of these elements 85 upon rotation of the rod 24. However, it is desired to prevent this simultaneous movement, which of course, correspondingly swings the bucket 33 around the shaft 27 as an axis, until a coin has been deposited in 90 the machine. I therefore mount on the base 18 a coin chute 44, which is disposed at an inclination and terminates at its lower end in a channel, generally designated 45, the outlet end of which is only of sufficient width 95 to permit the passage of a nickel therethrough. Lateral displacement of the nickel through the wider end of the channel is prevented by a resilient finger 46, which is mounted on the chute and has its free end 100 projected inwardly in the channel. As shown diagrammatically in Fig. 11 of the drawings, both sides of the channel 45 are included in the motor circuit, designated 47, the circuit wires being engaged with the opposite sides of the channel in order that the coin passing therethrough will bridge the gap between the said opposite sides of the channel and thereby close the circuit. The 105 motor circuit additionally includes a contact 110 plate 48, which is pivotally mounted upon the block 20 and an adjustable contact pin 49 also carried by the block 20. The motor circuit is connected to a suitable source of energy, indicated at 50, and is adapted to 115 include two or more plug sockets 51 mounted at convenient points on the base 18. When a coin passes into the channel 45, it bridges the gap in proximity to the lower end of the channel for closing the motor circuit, 120 thereby causing the motor to run for a short period of time, the duration of which is controlled by mechanism hereinafter described. The disc 26 is then permitted to be operated 125 in unison with the gear wheel 22. At this point it is apparent that the circuit between the plate 48 and pin 49 is broken and is not closed until after the disc 26 has been rotated to release an abutment 52, carried thereby, from contact with the plate 48, permit-

125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

ting the latter to flex into engagement with the pin 49.

To permit rotation of the disc 26 when the circuit is closed by the coin, I provide, on the base 18, a suitable unit 53, which includes rods, one of which has one end thereof bent at right angles to provide an attaching arm 54, to which I engage one end of a metal strap 55, the opposite end of the latter being engaged with the disc 26. When the circuit through the coin channel is closed, movement of the disc 26 is permitted to correspondingly rotate the shaft 27 and thereby position the bucket at any desired point above the articles 17 on the shelf 16. Rotation of the shaft 27 is at this time effected by turning the hand wheel 25 to give the operator a limited period of time for optional positioning of the bucket over the articles 17. The duration of this period is limited by the strokes of the arms 42, since as already stated, when one of said arms moves into its lowermost position, the parts of the bucket are permitted to open and by the time it is urged into its other extreme position, the bucket has been elevated by the other arm and at this point, the coin has been released by suitable mechanism hereinafter described.

To automatically effect release of the coin after it has been used to close the circuit in the manner already described, I preferably make one side of the channel 45 of the coin chute in two parts, the lower of which I designate 45' and the upper of which I designate 45². The part 45' is hinged on one of the uprights which supports the chute on the base 18 and the upper end thereof is normally urged inwardly by a spring 56. Said upper end bears against the lower end of the part 45² to normally urge said lower end of the upper part inwardly, which movement is limited by a stop 57. Sufficient pressure is in this way exerted by the spring 56 to cause the coin to be held before gravitating to the lower end of the chute channel, as shown to advantage in Fig. 8. A suitable automatic release means for the coin is provided through the medium of a bar 58 pivotally mounted upon the base 18, one end of which is engaged to one end of a cable 59, the opposite end of said cable being engaged with the part 45² of the channel 45. The end of the bar with which the cable 59 is engaged is normally urged in a direction away from the channel 45 by a spring 60, which is anchored on the base 18.

It now becomes apparent that as soon as the coin circuit is closed, a pin 43', which projects laterally from one pair of the links 43, will contact with a block 61 and ride over the bevel face 61' thereof. During this cycle of operation, optional positioning of the bucket over the articles 17 is permitted by turning the hand wheel 25. When the pin 43' clears the top of the block 61, freedom

of movement of the unit 53 is permitted in order that the disc 26, moving in a clockwise direction and exerting a pull on the metal strap 55, will correspondingly operate the unit 53 in a direction away from the motor 34. On the return stroke of the links 43 which carry the pin 43', the block 61 is intercepted to urge the unit engaging end of the bar 58 in the direction of the motor to release tension on the cable 59, permitting the coin to gravitate through the bottom of the channel. At the same time, operation of the disc 26 is effected by the pull exerted on the metal strap 55 when the unit 53 is urged in the direction of the motor.

If desired, a mechanical resistance unit for the motor may be employed, as shown in Fig. 3 of the drawings, including a yieldable connection element 62, one end of which is engaged with the motor shaft and the opposite end engaged with a plate 63, which may be adjusted on the base 18.

I also provide in the case a suitable article-delivery chute 64, the receiving end of which is at one end of the case and the dispensing end of which opens at the front of the case.

Preferably I include in the motor circuit 47 a lamp 47' which is mounted upon the base 18 for the purpose of illuminating the case.

In Fig. 12 I provide mechanical means for raising and lowering the crane 30, which consists of a lever 65 pivotally mounted on one side of the frame 19 and in engagement with one end of a cord 66, the latter being trained through an eye 67 on the shaft 27 and having its opposite end engaged with the crane. The operator may move the lever 65 in a vertical arc in order to correspondingly move the crane 30, thereby mechanically raising or lowering the bucket 33 for more advantageous positioning of the same over an article carried by the shelf 16.

It is manifest from a consideration of the motor circuit shown diagrammatically in Fig. 11, that the lamp 47' is illuminated when either one of the sockets 51 is plugged in. Moreover, although the hand wheel 25 may be rotated to correspondingly rotate the gear wheel 22, motion will not be imparted to the shaft 27 until the coin has been deposited in the chute 44 and the circuit closed through the sides of the channel thereof, in the manner already herein described. When this action takes place, movement of the hand wheel 25 then rotates the shaft to correspondingly turn the bucket 33 to the desired position over the shelf 16 and further movement is effected by the motor operated arms 42, as already described.

Although I have herein shown and described the preferred forms of my invention, it is nevertheless to be understood that various changes may be made in the construction, proportions and arrangement of parts, within the scope of the appended claims.

What is claimed is:

1. A vending machine in combination with a motor operated digging and hoisting mechanism, an electric circuit including said 5 motor, a coin chute associated with said mechanism and embodying a switch in said circuit operable to close the latter when a coin is deposited in the chute, and manually controlled means in connection with the digging 10 and hoisting mechanism to permit optional positioning of the latter only after the circuit has been closed by the coin. 70
2. A vending machine, as set out in claim 1, and mechanism also in the motor circuit and 15 in operative connection with the digging and hoisting mechanism to actuate the latter independent of the manually controlled means at the expiration of a predetermined interval after the closing of the circuit. 75
- 20 3. A vending machine including a base equipped with an upstanding rotatably mounted shaft, a cabin fixed on the top of said shaft with a crane hingedly mounted thereon, cables trained through said crane, 25 one end of each of which passes through the cabin and terminates adjacent said base, a shovel carried by the opposite ends of the cables, and a motor mounted on said base and operatively connected to said shaft and the 30 free terminals of the cables. 80
4. In combination with a vending machine embodying a base supporting a motor-operated digging and hoisting mechanism which includes a crane with a pair of cables 35 trained therethrough, one end of each of which engages the digging part of said mechanism, and arms mounted on the base and operatively connected with the motor, each of said arms being engaged with one of the 40 cables, and movable by the motor through a vertical arc to exert a stress on its cable as the arm moves to the base of the arc. 85
- 45 5. A vending machine including a base, digging and hoisting mechanism carried by the base, means mounted on said base and engaged with the digging and hoisting mechanism to raise and lower the digger of the latter, a motor mounted on said base and in operative connection with the digging and 50 hoisting mechanism to raise and lower the same, an electric circuit including said motor and digging and hoisting mechanism, a normally open switch in said circuit, and manually operated means on the base and 55 engaged with said mechanism for moving the latter in a horizontal arc only when the circuit switch is closed. 90
- 60 6. A vending machine including a base equipped with digging and hoisting mechanism, manually operated means rotatably mounted on the base and in operative connection with said mechanism to urge the latter into a predetermined position preparatory to beginning the digging operation, 65 a disc mounted on said means and movable 95
